E. M. ADAMS.
DISPENSING PUMP AND MIXER.
APPLICATION FILED APR. 29, 1919.

1,349,543.

Patented Aug. 10, 1920.

Inventor:
Edward M. Adams,

By his Attorney Wm. J. Reid.

UNITED STATES PATENT OFFICE.

EDWARD M. ADAMS, OF NEW YORK, N. Y., ASSIGNOR TO MORRIS H. PETIGOR, OF NEW YORK, N. Y.

DISPENSING-PUMP AND MIXER.

1,349,543.

Specification of Letters Patent. Patented Aug. 10, 1920.

Application filed April 29, 1919. Serial No. 293,434.

To all whom it may concern:

Be it known that I, EDWARD M. ADAMS, a citizen of the United States, and a resident of New York city, in the county of New York 5 and State New York, have invented certain new and useful Improvements in Dispensing-Pumps and Mixers, of which the following is a specification.

This invention relates to apparatus for dispensing beverages, such as used with soda fountains and the like. The device is especially adapted for use with a comparatively thin beverage such as milk, especially milk that contains a considerable portion of 15 cream, that requires to be agitated before it is pumped out, so that the milk and cream will be uniformly mixed in the container, and especially at that part from which it is delivered.

20 One object of the present invention is to provide an improved form of pump for this purpose, that will be simple in its construction and operation, so that the parts engaged by the milk can be readily taken apart for 25 cleansing.

A further object of the invention is to provide in connection with a dispensing-pump, of the character in which the pump members are suspended some distance below 30 a cover plate, a mixer that can be operated from a member projecting up through the cover plate, that will serve to agitate the beverage previous to the operation of the pump, and therefore is operable independent 35 of the pump members.

In the accompanying drawing showing one embodiment of my invention, Figure 1 is 40 a vertical section through the structure.

Fig. 2 is an elevation of the upper portion 45 only, on a reduced scale, taken at a right angle to the view in Fig. 1.

Fig. 3 is a horizontal section taken above the mixer.

Fig. 4 shows the arm that controls the 45 mixer.

As set forth herein, a pump member denoted generally by 4 is suspended from a cover plate 5, by two cylindrical members, being shown as held by a rod 6 on one side, and a pipe 7 on the other side, that passes upwardly through the cover plate, and has a curved portion 8 at the top, through which the fluid forced upwardly by the pump in the pipe 7 will find exit.

55 The pump as shown comprises a cylinder

9 secured to an annular base 10, the latter being closed by a bottom disk 11, that screws into the base 10. This base has openings 12 normally closed by a disk valve 13, that can slide upwardly on a bolt 14 secured to the 60 disk 11. The base 10 has an extension 15 extending outwardly and upwardly, and suitably apertured to have the pipe 7 screwed therein, that thereby communicates with the lower portion of the pump cylinder. On 65 the opposite side the base 10 has an ear 16 in which the supporting rod 6 is secured; by which means the base is rigidly connected with the cover plate 5.

A piston 17 slides in the cylinder 9, and has its piston rod 18 secured thereto, projecting upwardly through the cover 5. This cover has a dome portion 19 provided with a short guide sleeve 20, adapted to receive a sleeve 21 connected with the piston rod. 70 A sleeve 22 is secured to the dome 19 and extends downwardly from the cover, with a small opening in the bottom 23 of this sleeve, through which the piston rod 18 passes and is guided. A coil spring 24 surrounds the piston rod inside of the sleeve 22, with its lower end engaging the bottom 23. This spring it will be seen extends upwardly into the sleeve 21, and engages a top wall 25 in this upper sleeve. The tension 85 of this spring tends to force the sleeve 21 upwardly at all times, and holds it against a lock nut 26 mounted on the upper threaded end of the piston rod 18. This threaded end projects beyond the lock nut 26 and is 90 screwed into a hinge member 27, having parallel spaced apertured jaws. A lever 28 is pivoted in these jaws, and its lower end is hinged to a link 29 that is hinged on a bracket 30 secured to the cover plate. From 95 this construction it will be understood that when the handle is swung downward the sleeve 21 and piston rod 18 will be depressed, and move a piston 17 down through the pump cylinder until the lock nut 26 strikes the top of the guide sleeve 20. The valve 13 remaining closed, the fluid in the pump cylinder will be forced up through the pipe 7. When the handle is released, the now compressed coil spring 24 will raise the 105 piston rod and handle, and the piston will be elevated. The valve 13 will rise and the fluid in which the pump cylinder may be inserted, in a suitable container, will enter the pump cylinder, to be forced up through 110

- the pipe 7 at the next depression of the handle. It is obvious that the handle and link 29 might be omitted, and the operator would simply push downwardly on the upper 5 projecting portion of the piston rod member, that would cause the beverage to be forced up through the pipe 7; and on release the coil spring would return the piston rod and piston to former position.
- 10 When it is desired to clean the pump, the bottom disk 11 is simply unscrewed from the base frame 15, carrying the valve 13 with it, and these members can be readily cleansed, and the bottom replaced. It will be further 15 seen that the piston 18 is solid and contains no valve, and the only valve employed is the one in the removable bottom.
- Where a device of this character is used for a beverage that will separate readily, 20 such as milk containing a proportion of cream, it is necessary to cause agitation of the beverage to produce a uniform mixture, especially in the lower part of the container where the fluid enters the pump. And it is 25 further advisable to cause this mixing prior to any movement of the pump piston. For this purpose I provide a mixer arranged to operate between the pump cylinder and the cover, and which can be manipulated 30 from above the cover plate, and independent of the piston rod movement. I show a mixer in the form of a disk 31 with fan blades 32. This mixer has a central opening through which the piston rod 18 projects, and is further 35 shown as having recesses 33, 34, whereby the opposite blades are guided by the upright supporting members 6 and 7. As shown I provide a threaded flanged sleeve 35 that surrounds the piston rod 18 and receives the apertured disk 31. A threaded washer 36 engages the sleeve to secure the disk thereon. An arm 37 has a ring portion 40 that engages the sleeve 35, and is held thereon by the threaded washer or nut 45 36. A rod 38, having a head 39 at its upper end, slides in an opening in the cover 5, and at its lower end is secured to the arm 37 by lock nuts 41. It will be readily understood that moving the rod 38 up and 50 down by its head 39 will move the mixer up and down above the pump cylinder. By this means the beverage will be very strongly agitated, and the cream that would rise to the top can be forced downwardly, and a 55 uniform mixture produced. It will be further seen that the operating lever 28, being supported by a hinged link as 29, will give an easy movement of the piston rod sleeve 21 in the guide sleeve of the cover plate, and 60 will not cause a binding movement therein. It will be further understood that the mixer can be operated entirely independent of the piston of the pump, so that at each use of the pump to withdraw the beverage, the 65 fluid can be first thoroughly mixed.

What I claim is:—

1. In combination with a dispensing pump comprising a cover plate, a pump cylinder, a pair of cylindrical members rigidly supporting the cover elevated some distance 70 above the pump cylinder, a piston working in the pump cylinder, a piston rod for the piston projecting upward through the cover, a mixer guided to slide upon the piston rod up and down and independent of the piston rod movement, and a bar slidable through the cover and fast to said mixer at its lower end, whereby to move the mixer up and down independent of the movement of the piston and piston rod, said mixer being 80 guided by said supporting members.

2. In combination with a dispensing pump comprising a cover plate, a pump cylinder, a pair of cylindrical members rigidly supporting the cover elevated some distance above 85 the pump cylinder, a piston working in the pump cylinder, a piston rod for the piston projecting upward through the cover, a mixer having fan blades and a central opening, a threaded sleeve in the mixer opening 90 and slidable freely on the piston rod, an arm having an apertured end portion engaging said sleeve, a threaded washer on the threaded sleeve to clamp the arm on the sleeve, and a bar slidable in the cover plate with its 95 lower end secured to said arm, whereby the mixer can be operated from above the cover plate and independent of the piston movement.

3. In combination with a dispensing pump 100 comprising a cover plate, a pump cylinder, a pair of cylindrical members rigidly supporting the cover elevated some distance above the pump cylinder, a piston working in the pump cylinder, a piston rod for the piston projecting upward through the cover, a mixer having fan blades and a central opening, a threaded sleeve in the mixer opening 105 and slidable freely on the piston rod, an arm having an apertured end portion engaging said sleeve, a threaded washer on the threaded sleeve to clamp the arm on the sleeve, and a bar slidable in the cover plate with its lower end secured to said arm, whereby the mixer can be operated from above the 110 cover plate and independent of the piston movement, said disk being guided by said cylindrical supporting members.

4. The combination of a cover plate having a central opening and a guide sleeve projecting upwardly therefrom, a pump cylinder, a pair of cylindrical members supporting the cover plate elevated from the cylinder, a piston working in the cylinder, a piston rod projecting up from the piston through the guide sleeve, a sleeve extending downward from the guide sleeve and having a small opening in its bottom through which the piston rod travels, a coil spring around the piston rod seated in the said 115 120 125 130

sleeve bottom and projecting upwardly through both said sleeves, a sleeve member freely slideable in the said guide sleeve and having a top portion with a reduced opening surrounding the piston rod, said coil spring having its upper end seated in said latter sleeve top tending to force said sleeve upwardly, said piston rod having its upper

end secured to said slideable sleeve, whereby depression of the rod and sleeve will compress the coil spring and depress the piston in the pump cylinder. 10

Signed at New York City, N. Y. on April 28th, 1919.

EDWARD M. ADAMS.
